(57) **CLAIM**

The ornamental design for a side shelf, as shown and described.

DESCRIPTION

FIG. 1 is an isometric view from the top, front and right side of the side shelf of the present invention as it attaches to a cabinet;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is an isometric view of the rear, left side and bottom thereof with the inner facing edge surfaces of the left side and right side being symmetric with each other;

FIG. 9 is an isometric view of the left side, front and underside of the top thereof with the inner facing edge surfaces of the left side and the right side being symmetric with each other;

FIG. 10 is an isometric view of the left side, rear and bottom thereof; and,

FIG. 11 is an isometric view of the rear, left side and underside of the top thereof.

That which is depicted in solid lines in the drawing represents the claimed invention and that which is depicted in broken lines in the drawing forms no part of the claimed invention. Portions of surfaces that are not shown in the drawing are flat, plain and unornamented.

Where rounded broken line edges are shown at the corners of the shelves, it is understood that these broken lines represent the bounds of the claimed design.
